UNITED STATES PATENT OFFICE.

PENTON A. HARDWICK, OF COLORADO CITY, COLORADO.

WASHING-MACHINE.

SPECIFICATION forming part of Letters Patent No. 660,481, dated October 28, 1900.

Application filed November 4, 1899. Serial No. 735,788. (No model.)

To all whom it may concern:

Be it known that I, PENTON A. HARDWICK, a citizen of the United States, and a resident of Colorado City, in the county of El Paso and 5 State of Colorado, have invented a new and Improved Washing - Machine, of which the following is a full, clear, and exact description.

The object of my invention is to simplify 10 and improve the construction of that class of washing-machines provided with means for the introduction of steam into the washing-chamber and to so construct the machine that it may be used for drying feathers or clothes 15 or articles of a similar nature or may be used for dampening clothes for ironing.

The invention consists in the novel construction and combination of the several parts, as will be hereinafter fully set forth, 20 and pointed out in the claims.

Reference is to be had to the accompanying drawings, forming a part of this specification, in which similar characters of reference indicate corresponding parts in all the figures.

25 Figure 1 is a side elevation of the improved machine. Fig. 2 is a vertical section taken practically on the line 2 2 of Fig. 3. Fig. 3 is a section taken at right angles to the section shown in Fig. 2 on the line 3 3 of 30 Fig. 2 and a side elevation of a receptacle for generating steam connected with the machine.

The body A of the machine is in the form 35 of a semicircular tub supported on suitable legs 10. A transverse opening 11 is made in the bottom of the tub, covered by a screen 12, and said opening 11 connects with an inclined chute 13, which may be closed at its outer end by a stopper 14 or an equivalent of 40 a stopper. This chute is adapted to collect the dirt washed out from the clothes and to serve as a medium for readily emptying the tub.

A cover B is provided for the body A, and 45 this cover is also of semicircular shape and is fitted upon the body in a steam-tight manner. Both the body and cover are preferably made of wood and are finished in an air-tight manner. The cover is also provided 50 at its sides with handles 15, so that it may readily be removed.

A cylinder C, adapted to contain the clothes, is held to revolve partially within the body and partially within the cover for the body or tub. This cylinder usually consists of two 55 metal heads 16, provided with inwardly-extending flanges 17, the heads being strengthened by X-braces 18, secured to their inner faces, as shown in Figs. 2 and 3, and the cylinder is completed by adding a peripheral 60 covering 19, of galvanized wire, provided with a suitable door 20, and the cylinder is also provided with paddles 21, extending along the screen-periphery from head to head, the said paddles being secured to the braces 18 in any 65 suitable or approved manner. As the cylinder is rotated these paddles move the clothes upward and cause them to fall from an upper to a lower position within the cylinder. The cylinder is provided with trunnions 22, 70 journaled in suitable bearings in the body or tub A, as is shown in Fig. 3, and one trunnion is provided with a sprocket-wheel 23, which is connected by a chain belt 24 with a smaller sprocket-wheel 25, provided with a 75 handle 26 and mounted upon a bracket 27, located upon the exterior of the tub or body of the machine, as is shown in Fig. 1. A nozzle 28 is in communication with the interior of the body at one side near one end, 80 and this nozzle is adapted to receive a flexible tube 29, which is also connected with a pot or a kettle D or a like vessel, in which water may be kept boiling upon a stove or range. The tube 29 serves to conduct steam 85 into the interior of the machine and keep the washing material in a heated condition, which greatly facilitates the cleansing of the clothes.

The machine is provided at its bottom with 90 an auxiliary casing 30, which is eccentric to the main bottom, as shown in Fig. 2, thus providing a chamber 31, and at the upper portion of the said chamber 31, at one side, a nozzle 32 is located. At the upper portion of the said chamber, at the opposite side of the machine, a second nozzle 33 is located. The nozzle 32 has communication only with the chamber 31, while the nozzle 33 is so made that it connects not only with the chamber 95 31, but also with the interior of the tub and with the outside atmosphere. The nozzle 33

is usually provided with two stoppers 34, one at each end, although but a single stopper may be used, if desired.

When the machine is to be used for drying clothes or feathers, the steam-delivery pipe 29 is connected with the nozzle 32 and the outer stopper 34 is removed from the steam-outlet 33, and the steam entering the chamber 31 will heat the tub and dry its contents, it being understood that the cylinder C may be utilized to receive the material to be dried or that the material may be placed directly in the tub A. Under the same conditions when it is desired to dampen clothes for ironing steam is admitted at the nozzle 32, and the outlet 33 for the steam is closed at its outer end and opened at its inner end, enabling the steam to come in direct contact with the clothes. When the machine is used in this manner, a large number of clothes may be simultaneously dampened for ironing, the clothes will be uniformly dampened, and the necessity of sprinkling the clothes singly is avoided.

Having thus described my invention, I claim as new and desire to secure by Letters Patent—

1. In a washing-machine, a tub, a steam-tight cover therefor, the said tub being provided with a double bottom and an outlet and

a grating adjacent to the outlet, the outer section of the bottom being eccentric to the inner section, a nozzle leading into the upper portion of the chamber formed by the double bottom of the tub, a double nozzle communicating with the said chamber and with the exterior and interior of the tub, plugs for the inner and outer ends of the double nozzle, and a third nozzle connected directly with the interior of the tub and located at one side of the same, substantially as specified.

2. In a washing-machine, a tub provided with a double bottom having an outlet, a grating adjacent to the outlet, the outer section of the bottom being eccentric to the inner section, a nozzle leading into the upper portion of a chamber formed by the double bottom of the tub, a double nozzle communicating with the said chamber and with the exterior and interior of the tub, means for closing said double nozzle, and a third nozzle connected directly with the interior of the tub, substantially as specified.

In testimony whereof I have signed my name to this specification in the presence of two subscribing witnesses.

PENTON A. HARDWICK.
